UNITED STATES PATENT OFFICE

RONALD H. DALLAS, OF LONG BEACH, CALIFORNIA

DESIGN FOR A REFRIGERATOR BOTTLE

Application filed June 15, 1932. Serial No. 44,087. Term of patent 3½ years.

To all whom it may concern:

Be it known that I, RONALD H. DALLAS, a citizen of the United States, and a resident of Long Beach, in the county of Los Angeles and State of California, have invented a new, original, and ornamental Design for a Refrigerator Bottle, of which the following is a specification, reference being had to the ac-

companying drawing, forming a part thereof.

Figure 1 is a side view of the bottle.

Figure 2 is an edge view of the same.

Figure 3 is a top plan view of the bottle.

I claim:

The ornamental design for a refrigerator bottle, as shown.

RONALD H. DALLAS.
